UNITED STATES PATENT OFFICE.

ALFRED H. WHITESIDE AND SAMUEL G. CAMPBELL, OF LOGANSPORT, INDIANA.

BOOKBINDER'S VISE.

SPECIFICATION forming part of Letters Patent No. 727,520, dated May 5, 1903.

Application filed May 28, 1902. Serial No. 109,344. (No model.)

To all whom it may concern:

Be it known that we, ALFRED H. WHITESIDE and SAMUEL G. CAMPBELL, citizens of the United States, residing at Logansport, in the county of Cass and State of Indiana, have invented certain new and useful Improvements in Bookbinders' Vises, of which the following is a specification.

This invention relates to bookbinding, and has special reference to an improved bookbinders' vise or stand comprising means for permitting of the free use of both hands in the operation of lettering, gilding, or otherwise finishing the back of a book.

To this end the invention contemplates a simple and practical construction of vise designed to support books of various sizes in an upright position within convenient reach of the bookbinder and also in such a manner that the book can be very quickly removed and replaced.

In carrying out these general objects the invention contemplates a construction adapted for general use as a bookbinder's vise for holding the books clamped in a stationary or rigid position for any purpose.

With these and many other objects in view, which will more readily appear as the nature of the invention is better understood, the same consists in the novel construction, combination, and arrangement of parts, as will be hereinafter more fully described, illustrated, and claimed.

The essential features of the invention involved in the means for adjustably supporting the book and also in the adjustable and releasable means for clamping the book in its upright position are necessarily susceptible to considerable modification without departing from the spirit or scope of the invention; but a preferred embodiment of the latter is shown in the accompanying drawings, in which—

Figure 1 is a perspective view of a bookbinder's vise constructed in accordance with the present invention and showing a book clamped in an upright position to permit of the finishing operation, such as lettering, gilding, or the like. Fig. 2 is a vertical sectional view of the vise, showing one of the ways in which it may be conveniently secured

to a work table or bench. Fig. 3 is a detail sectional view showing more plainly the hinged connection between the swinging bracket and the adjustable clamp-carrier. 55 Fig. 4 is a detail sectional view showing the slip-clutch connection between the adjustable clamp-carrier or carrier-arm and the supporting member or cleat. Fig. 5 is a detail sectional view on the line 5-5 of Fig. 2 60

Like reference-numerals designate corresponding parts throughout the several figures of the drawings.

In carrying out the invention there is necessarily employed a fixed member or element, 65 against which the book is clamped, and usually this fixed member or element is in the form of an upright flat clamping-base 1, which is sufficiently wide at the upper portion thereof to provide an extended surface, upon which 70 one side of the book bears when clamped up in the vise. The said flat clamping-base 1 may be supported in any convenient manner, but is usually arranged in an upright position and is designed to be fastened to a work 75 table, bench, or other point convenient to the bookbinder. A simple means of mounting the upright clamping-base 1 of the vise in proper operative position is shown in the drawings and essentially consists in rigidly 80 securing to the rear side of the base, at or contiguous to the upper end thereof, a transverse cleat or bar 2, constituting the supporting member of the vise and having associated therewith a fastening-clamp 3, also secured 85 to the rear side of the upright base and below the plane of the cleat or bar 2, the screw member 4 of the clamp 3 being adapted to work against the under side of the work table or bench, whereby the latter may be clamped 90 between said clamp 3 and the cleat 2, thus providing for rigidly yet detachably fastening the vise in an operative upright position.

To provide for the support of a book and also for supporting books of greatly-varying sizes, there is associated with the upright clamping-base 1 a vertically-adjustable rest-platform 5, projected outwardly from the fixed base 1 and having its supporting-surface for the book disposed at right angles to 100 the adjacent side of the base, whereby the book may rest upon edge on the platform 5

and be clamped with its side flat against the base member 1.

Various expedients may be resorted to in providing for the vertical adjustment of the rest-platform 5 and also for locking the same fast in its adjusted position. A preferable construction is shown in the drawings, and consists in fastening the rest-platform 5 to an adjustable slide 6, adjustable longitudinally upon the clamping-base 1 and essentially consisting of the oppositely-arranged binding-plates 7 and 8, disposed, respectively, upon opposite sides of the base and one of which carries the intermediate slide-block 9, working in the slotted guideway 10, formed longitudinally in the base and usually extending the full length thereof, as shown in the drawings. The locking-screw 11 passes through the binding-plates 7 and 8 and a nut 12. This locking-screw 11 when tightened serves to clamp up the separate members of the slide 6, thus securely fastening the rest-platform 5 in any adjusted position.

The clamping of the book against the flat base 1 is accomplished through the medium of an adjustable clamp 13, working in opposition to the base 1 at the outer side thereof. This clamp-jaw has a swiveled connection 14 with the inner end of a clamping-screw 15, having a hand-wheel 16 at its other end and working through a nut 17, carried at the swinging or free end of a swinging bracket or bracket-arm 18. To permit of the adjustment inward and outward of the clamp-jaw 13 without turning thereof, said jaw preferably has a loosely-interlocked slidable connection with the bracket or bracket-arm 18. A preferable form of this connection is shown in the drawings and comprises a keeper consisting of a pair of spaced holding-pins 19, projected outward from the outer side of the clamp-jaw and sufficiently long to permit of a considerable adjustment of the clamp-jaw. The outer end portion of the bracket 18 is hinged by the hinge-pin 20 to the outer end of an adjustable clamp-carrier 21. The hinge-pin 20 for the bracket 18 is disposed longitudinally with reference to the carrier 21 and transversely with reference to the bracket 18, which is rounded off at its rear end, as shown in Fig. 3, whereby the same may swing upwardly and laterally to provide for moving the clamp in and out of operative position, according as the book is to be mounted in position or removed. At the point of the hinge connection between the bracket and its supporting-carrier 21 the latter is provided with a transversely-disposed seat 22 in its upper side, within which seat the bracket 18 lies flush when in its lowered operative position. It will here be noted that the bracket 18 and the carrier-arm 21 constitute a support for the jaw 13.

The adjustable clamp-carrier 21 is preferably in the form of a straight bar and usually extends through a clutch-opening 25, formed in one end portion of the cleat or bar

2. One wall of the clutch-opening 25 is formed with a binding swell or projection 26, against which the carrier or bar 21 is rocked or pressed when the clamping-screw 15 is tightened up. By reason of this construction it is obvious that the locking of the clamp-carrier 21 is automatic, but when the screw 15 is loosened the said bar may be readily slid through the clutch-opening to accommodate the clamp to any size book.

From the foregoing it is thought that the construction, operation, and many advantages of the herein-described bookbinder's vise will be readily apparent without further description, and it will also be understood that various changes in the form, proportion, and minor details of construction may be resorted to without departing from the spirit of the invention or sacrificing any of the advantages thereof.

Having thus described the invention, what is claimed, and desired to be secured by Letters Patent, is—

1. In a vise of the class described, a fixed upright base, a substantially horizontal rest-platform adjustable vertically on the base, and a support having a jaw-carrying member mounted to move vertically into and out of an operative position with respect to the base, the space between and above the base and the jaw-carrying member being unobstructed to give access to the back of a book when held in the vise.

2. In a vise of the class described, a fixed base, a rest-platform adjustable on the base, and an adjustable clamp-support comprising a carrier and a jaw-carrying bracket movable upon the carrier to operative and inoperative positions.

3. In a vise of the class described, a fixed base, a rest-platform for a book, and a clamp-support comprising an adjustable clamp-carrier and a jaw-carrying bracket having a hinge connection with the carrier.

4. In a vise of the class described, a fixed base, a rest-platform for the book, and an adjustable clamp-support comprising a slidably-supported clamp-carrier provided at its outer end with a transversely-disposed seat, and a laterally-swinging jaw-carrying bracket having a hinged connection with the said carrier and adapted to rest within the seat thereof.

5. In a vise of the class described, an upright clamping-base having a supporting member provided with a clutch-opening therein, a rest-platform for the book and an adjustable clamp-support comprising a bracket member carrying a clamp-jaw and an adjusting-screw therefor, and a bar having an adjustable clutch engagement with the said clutch-opening.

6. In a vise of the class described, an upright clamping-base having a supporting member, a rest-platform for the book, an adjustably-supported bracket having a nut, a movable clamp-jaw having a loosely-interlocked engagement with the bracket, and a

clamping-screw mounted in said nut and having a swiveled connection at its inner end with said jaw.

7. In a vise of the class described, the combination of an upright flat clamping-base, a clamping-jaw movable horizontally toward and away from the base, a jaw-support having a vertically-swinging member, the jaw being mounted upon said member to be swung vertically therewith into and out of operative position and a substantially horizontal rest-platform having a slide movable vertically

upon the base and provided with a locking device, the space between and above the base and the jaw being unobstructed to give access to the back of a book when in the vise. 15

In testimony whereof we affix our signatures in presence of two witnesses.

ALFRED H. WHITESIDE.
SAMUEL G. CAMPBELL.
